Primary Examiner—Alan P. Douglas**Assistant Examiner**—M. N. Pandozzi**Attorney, Agent, or Firm**—Burd, Bartz & Gutenkauf**[57]****CLAIM**

The ornamental design for a water bottle dispenser, as shown and described.

DESCRIPTION

FIG. 1 is a top, front left side perspective view of a water bottle dispenser showing my new design;

FIG. 2 is a left side elevational view thereof;

FIG. 3 is a top plan view thereof;

FIG. 4 is a front elevational view thereof;

FIG. 5 is a right side elevational view thereof;

FIG. 6 is a rear elevational view thereof; and,

FIG. 7 is a bottom plan view thereof.
